UNITED STATES PATENT OFFICE

132,134

DESIGN FOR A BADGE OR THE LIKE

Grover C. Potts, Big Spring, Tex.

Application June 3, 1941, Serial No. 101,267

Term of patent 3½ years

To all whom it may concern:

Be it known that I, Grover C. Potts, a citizen of the United States and a resident of Big Spring, in the county of Howard and State of Texas, have invented a new, original, and ornamental Design for Badge or the like, of which the following is a specification, reference being had to the accompanying drawing, forming part thereof, in which

I claim:

The ornamental design for a badge or the like, substantially as shown.

GROVER C. POTTS.
